UNITED STATES PATENT OFFICE.

JACOB R. SCOTT, OF NEW YORK, N. Y.

SKIVING-MACHINE.

SPECIFICATION forming part of Letters Patent No. 467,441, dated January 19, 1892.

Application filed August 20, 1891. Serial No. 403,231. (No model.)

To all whom it may concern:

Be it known that I, JACOB R. SCOTT, a citizen of the United States, residing at New York, county and State of New York, have 5 invented new and useful Improvements in Skiving-Machines, of which the following is a specification.

This invention relates to a skiving-machine which is intended particularly for preparing the inner surfaces of soles for boots or 10 shoes, but which can also be used for other articles.

The improvements which form the subject-matter of my present invention are pointed 15 out in the following specification and claims, and illustrated in the accompanying drawings, in which—

Figure 1 represents an end view looking in the direction of arrow 1, Fig. 2. Fig. 2 is a rear 20 elevation looking in the direction of arrow 2, Fig. 1. Fig. 3 is a transverse section in the plane x x , Fig. 2. Fig. 4 is a longitudinal section of the roller-die. Fig. 5 is a transverse section of the roller-die. Fig. 6 is a section 25 similar to that shown in Fig. 3, but showing the parts in a different position. Fig. 7 is a plan of a sole prepared on my machine.

In the drawings, the letter A designates the bed-plate, from which rise two standards 30 B B, which form the bearings for the shaft C. On this shaft is firmly mounted the roller-die D, which is provided with swells or protuberances d d , between which is formed a depression d' . If the machine is to be used for 35 soles of boots or shoes, the inner edges of the protuberances d d are semicircular, to correspond to the inner edges of the shank portions d^o d^o of the sole S, Fig. 7. The shaft C is geared by cog-wheels a a with a counter- 40 shaft C', which carries the feed-roller D' and which has its bearings in two arms E E, and which extend from eyes F, mounted loosely upon the counter-shaft C'. The rear ends of the arms E E are exposed to the action of 45 springs b b, which have a tendency to force the feed-roller D' up toward the roller-die D. Set-screws c c serve to regulate the upward motion of the feed-roller D'. The surface of this feed-roller is fluted, so as to enable the 50 same to take a firm hold of the article to be fed toward the knife H. This knife extends

between the rollers D D', and it is secured to a bracket h, which is adjustably secured to one of the standards B by means of a screw h', which passes through a slot in the bracket. 55 A screw h² serves to adjust the bracket up and down, and the knife is secured to the bracket h by means of screws h³, which pass through slots in the knife, so that the cutting-edge of the latter can be adjusted in the 60 required position toward the roller D D'.

From the eyes F extend arms G G, which swing upon the driving-shaft I. This driving-shaft has its bearings in the standards B B, and it carries a belt-pulley J and a pinion 65 K, which gears with a cog-wheel L, mounted loosely on the shaft C. The hub l of the cog-wheel L extends into a clutch-section M, which is firmly mounted on the shaft C and which carries a pawl m, which, when free to follow the action of a spring n, Fig. 3, engages one of the teeth t, formed on the hub l of the cog-wheel L. When the pawl m is in engagement with this tooth, the cog-wheel M is thrown in gear with the shaft C and the rollers D D' are set in motion. The pawl m can be thrown out of gear with the hub of the cog-wheel L by means of a lever N, which swings on the driving-shaft and connects by a rod O with a treadle, (not shown,) and in the outer end N' of the lever N is secured a dog n³, which, when the treadle is depressed to the position shown in Figs. 2 and 3, rides upon the circumference of the clutch M, and as soon as it meets the tail of the pawl m the pawl is raised to the position shown in 75 Fig. 3 and the motion of the rollers D D' stops. The dog n³ is secured to the arm N' by a screw n', which passes through a slot, so that when said screw is loosened the dog n³ can be moved in or out. A screw n² serves to adjust the dog 80 in the required position. The object of this arrangement is to adjust the machine for soles of different lengths, as will be presently more fully explained. Immediately after the treadle has been permitted to rise and the rollers D 85 D' have been started the treadle is again depressed, so that when the rollers have completed one revolution the pawl m is thrown out of gear with the hub of the cog-wheel L and the motion of the rollers is stopped. 90

The roller-die D is provided with a sharp-edged tooth p, which is secured to a block p', 95

- which fits a groove p^2 in the roller-die and can be fastened in the required position by a set-screw q . When the sole or other article is pushed in between the rollers D D', the tooth 5 p enters the front edge of the sole and retains the same upon the roller-die D, while that portion of the sole which comes in contact with the edge of the knife H is cut away during the revolution of the rollers D D'. The tooth 10 p must be adjusted so that its distance from the beginning of the protuberances $d d$ (measured on the circumference of the roller-die) is equal to the distance between the tip of the sole S and the front ends of the shank portions $d^o d^o$, Fig. 7. For soles of greater length 15 the tooth p must be moved in the direction of arrow 1, Fig. 5, and the length of the dog n^3 must be reduced, and for shorter soles the tooth p is moved in the opposite direction and 20 the length of the dog n^3 is increased.

I do not claim in this application for a patent anything shown and described in an application filed by me July 1, 1891, Serial No. 308,269.

- 25 What I claim as new, and desire to secure by Letters Patent, is—

1. In a skiving-machine, the combination, with the splitting-knife H, of a feed-roller D', arranged below the knife, a roller-die D, arranged 30 above the knife and provided with protuberances $d d$ and a depression d' between the protuberances, a sharpened tooth p , projecting outward from the periphery of the roller-die for penetrating the leather sole, and 35 means for rotating the rollers, substantially as described.

2. In a skiving-machine, the combination of a vertically-adjustable bracket h , carrying a horizontal splitting-knife H, means for holding 40 the bracket in any position of adjustment, a feed-roller D', arranged below the knife, a roller-die D, arranged above the knife and provided with protuberances $d d$ and a depression d' between the protuberances, a 45 sharpened tooth p , projecting outward from the periphery of the roller-die for penetrating the leather sole, and means for rotating the rollers, substantially as described.

3. The combination of the feed-roller D', 50 the roller-die D, provided with protuberances $d d$ and a depression d' between the protuberances, a vertically-movable bracket h , slideable on the machine-frame and carrying a horizontal splitting-knife H at its upper end, 55 which projects between the feed-roller and the roller-die, and means for rigidly securing

the bracket in different positions on the machine-frame, substantially as described.

4. The combination, in a skiving-machine, of shaft C, journaled on the machine-frame 60 and having a roller-die D, the drive-shaft I, geared to the roller-die shaft, the spring-pressed arms E, suspended from the drive-shaft and geared to the roller-die shaft, the counter-shaft C', mounted in the spring-pressed arms, the vertically-movable bracket h , slideable on the machine-frame and carrying a horizontal splitting-knife H at its upper end, 65 which projects between the feed-roller and roller-die, a screw h' , passing through the bracket and engaging the machine-frame, and a set-screw h^2 , connecting the machine-frame with the lower end of the bracket, substantially as described.

5. The combination, with a splitting-knife 75 H, of a feed-roller D', arranged below the knife, a roller-die D, arranged above the knife, a sharpened tooth p , projecting outward from the periphery of the roller-die for penetrating the leather sole, and means for rotating the 80 feed-roller and roller-die, substantially as described.

6. The combination, with the knife H, of a feed-roller D', a roller-die D, having a longitudinal groove, a block arranged in the groove 85 and provided with a sharpened tooth which projects outward from the periphery of the roller-die for penetrating the leather sole, a set-screw for adjusting the block in the groove of the roller-die, and means for rotating the 90 feed-roller and roller-die, substantially as described.

7. In a skiving-machine, the combination, with the knife H, the shafts C C', the feed-roller D', and the roller-die D, mounted on 95 said shafts, the driving-shaft I, the cog-wheel L, geared with the driving-shaft and having a toothed hub l , and the clutch M, having the pivoted pawl m , of the lever N, provided with the adjustable dog n^3 , means for adjusting 100 the dog to different positions on the lever, and devices for operating the lever to move the dog into the path of the pawl, substantially as described.

In testimony whereof I have hereunto set 105 my hand in the presence of two subscribing witnesses.

JACOB R. SCOTT.
